UNITED STATES PATENT OFFICE.

LISLE J. DARE, OF SPOKANE, WASHINGTON.

WALL CONSTRUCTION.

1,080,002.

Specification of Letters Patent.

Patented Dec. 2, 1913.

Application filed March 3, 1913. Serial No. 751,703.

To all whom it may concern:

Be it known that I, LISLE J. DARE, citizen of the United States of America, residing at Spokane, in the county of Spokane and 5 State of Washington, have invented certain new and useful Improvements in Wall Construction, of which the following is a specification.

This invention pertains to construction of 10 hollow walls and has for its object to improve the construction of walls of stone, brick, concrete or other material where it is desired to provide for a hollow space between the main walls and the plastering, 15 and have such walls fire proof and damp proof.

The foregoing and other purposes are accomplished by the addition and use in such construction of a wall-tie of special design 20 and construction and which I have invented and which, together with the connection and application of the same, will be hereinafter described and illustrated in the accompanying drawings, in which—

25 Figure 1, is a perspective view of the wall-tie, Fig. 2, is a side view of the same, Fig. 3, is a side view of the wall tie shown in position in a fragmental portion of a cement wall in course of construction, showing 30 fragmental sectional views of the cribbing inclosing the cement, and Fig. 4, is a side view of the wall-tie shown in position in a fragmental cement wall and applied to a fragmental portion of metal lath with the 35 plastering in position on the same.

In detail construction the wall-tie 10 is composed of a sheet metal main body 11 having at one end oppositely bent tongues 12, at the opposite end marginal teeth 13, 40 and near the longitudinal center thereof marginal, vertically arranged guides 14. A downwardly extending spur 15 reaches from a position near the guides 14.

The entire construction of the wall-tie 10 45 is of one piece of metal and may be stamped out and bent to position. The tie 10 is placed in the wall 16 when in course of construction with the portion 11 in a horizontal position, the tongues 12 in a vertical position, the guides 14 in a vertical position and 50 engaging the inner wall of the cribbing 17 and the face 18 of the wall 16. The spur

15 is embedded in the top, horizontal wall 19 of the cribbing 17 which serves to hold the tie 10 in its proper position until the 55 cement or concrete 16 is firmly set, after which the cribbing is removed as usual and the tie 10 occupies the position in the wall 16 shown in Fig. 4. The ties 10 are thus set at proper distances apart in the wall 16, 60 as the same is being constructed, and are of uniform length with the portions 20 extending outwardly a uniform distance from the face 18 of the wall 16, when the metal lath 21 are inserted over the end of the tie 10 65 carrying the teeth 13, the lath 21 bearing against the edge 22 with the teeth 13 protruding through the same which are then bent to vertical positions in opposite directions as shown in Fig. 4, serving to firmly 70 bind the lath 21 in uniform position with the ties 10 when the plastering 23 is placed upon the lath 21 and the wall is complete leaving a uniform space 24 (Fig. 4) between the wall 16 and the plastering 23. 75 The ties 10 are inexpensive and light and leave the completed wall without any wooden studding or construction whatever.

What I claim is,

1. A sheet metal wall-tie, comprising a 80 flat body portion, tongues at one end thereof bent to approximately right angles with the body portion, guides near the center of the body portion bent to right angles therewith and teeth at the end of the body portion opposite the tongues, the same being horizontal with the body portion.

2. A sheet metal wall-tie, comprising a 85 flat body portion, tongues at one end thereof oppositely bent to approximately right angles with the body portion, guides near the center of the body portion bent to right angles therewith, teeth at the end of the body portion opposite the tongues and a spur reaching from the body portion at a 90 position between the guides and the teeth and extending in a position approximately parallel with the guides.

In testimony whereof I affix my signature in the presence of two witnesses.

LISLE J. DARE.
